FORGING DIE AND MOUNT ASSEMBLY

Floyd H. Wyman and Joseph M. Malik, Toccoa,
Ga., assignors to R. G. Le Tourneau, Inc.,
Stockton, Calif., a corporation of California

Application November 17, 1942, Serial No. 465,860

5 Claims. (Cl. 78—96)

1

This invention relates in general to forging dies and mounts therefor, and the invention has for its principal object the provision of a forging die and mount assembly which is arranged to facilitate placement of the work in the die, and removal of the forging from the die after the forming operation; the device being especially designed for use in power forging presses.

A further object of this invention is to provide a forging die and mount assembly in which the die is normally upstanding and opens upwardly; said die being mounted for tip-over movement from said upstanding position to a position opening laterally, whereby to permit the ready insertion of the work in the die, or the removal of the forging therefrom, particularly when the space between the head of the power press and the top of the die is limited, or in any instance where horizontal or lateral removal of the forging is more desirable.

An additional object of this invention is to provide a forging die and mount assembly, as above, in which mechanism, either hand or power actuated, is connected with the die to tip the same between its upstanding and its tipped-over position.

It is also an object of this invention to provide a forging die and mount assembly in which the die is of cavity type, normally upstanding and opens upwardly, being mounted for tip-over movement from said upstanding position to a position opening laterally; the die having a bottom opening, and the assembly including a movable forging drive-out rod normally mounted clear of the die but adapted to project at one end through said bottom opening and to strike the forging when the die is in tipped-over position, said drive-out rod being manually actuated in one embodiment of the invention, and power actuated in another embodiment of the invention.

A further object of the invention is to produce a simple and inexpensive device and yet one which will be exceedingly effective for the purpose for which it is designed.

These objects we accomplish by means of such structure and relative arrangement of parts as will fully appear by a perusal of the following specification and claims.

In the drawings similar characters of reference indicate corresponding parts in the several views:

Figure 1 is a side elevation of the forging die mount assembly, illustrating an embodiment wherein the die tip-over mechanism and the forging drive-out rod are both manually actuated.

Figure 2 is a fragmentary longitudinal sectional elevation showing the die in tipped-over position and the forging drive-out rod in use.

Figure 3 is a side elevation of the forging die and mount assembly, illustrating an embodiment

wherein the forging drive-out rod is power actuated.

Figure 4 is a side elevation of a forging die and mount assembly, illustrating an embodiment wherein the die tip-over mechanism is power actuated.

Referring now more particularly to the characters of reference on the drawings, and at present to the embodiment of Figs. 1 and 2, the forging die and mount assembly comprises a horizontal elongated base 1 adapted to be removably secured to the bed 2 of the forging press by means of bolts 3. An upstanding die holder 4 is normally seated on the base 1 adjacent one end thereof; said die holder surrounding and supporting an upstanding cavity die 5 which includes a vertical work receiving bore 6 open to the top 7 of said die.

The die holder 4 and the supported die 5 are mounted for pivotal tipping movement longitudinally of the base 1 and toward the adjacent end, by means of transversely spaced ears 8 on the die holder adjacent its lower end pivoted, as at 9, to cooperating ears 10 mounted on the base 1. A stop 11 on the base limits tip-over movement of the die holder to a position with the die bore 6 opening horizontally.

A horizontal longitudinally extending forging drive-out rod 12 is supported above the base 1 beyond the die holder, in a direction opposite to the direction of tip-over movement of the latter, by upstanding longitudinally spaced guide brackets.

The bottom of the die is formed with a central port 14 of a diameter less than the diameter of bore 6, and the rod 12 aligns with and is adapted to project through said port when the die holder and die are in tipped-over position. At the end opposite the die holder the rod 12 is formed with an enlarged head 15, and a shock-absorbing compression spring 16 surrounds the rod 12 between head 15 and the adjacent guide bracket 13. As is shown in Fig. 1 the drive-out rod 12 is normally clear of the die holder 4.

The die tip-over arrangement comprises a bell crank lever 17 pivoted at 18 in connection with the base 1 for swinging movement in a vertical plane lengthwise of said base; one leg 19 of the bellcrank 17 being relatively short and normally projecting upwardly, while the other leg 20 is normally substantially horizontal and is elongated to form a handle. A rigid link 21 is pivotally connected between the upper end of leg 19 and the adjacent side of the die holder 4 at a point intermediate the ends of, and in tip-over relation to the latter.

Operation

In the present instance, the die 5 is of the type used in connection with the formation of cylin-

drical forgings P, such as headed pins. After the forging P has been formed by the press in the upstanding die 5, the hand lever 20 of bellcrank 17 is swung upward, which causes the die holder to tip over to the laterally opening position shown in dotted lines in Fig. 1. Thereafter the operator strikes the head 15 of rod 12 with a sledge hammer, which causes said rod to project at the other end through die port 14 and forcefully strike the adjacent end of the forging P, driving the latter out of the die. The spring 16 serves as a shock absorber for the blow imparted to head 15.

After the forging has thus been removed from the die the hand lever 20 is returned to normal horizontal position, which causes the die holder and die to likewise be returned to upstanding position for the next forging operation.

In the embodiment shown in Fig. 3 the die holder 4 and die 5 are mounted on the base 1, as above described, and are tipped from upstanding to laterally opening position by a link 21a and a bellcrank 17a arranged in a manner similar to that above described in connection with link 21 and bellcrank 17.

In this embodiment, however, the forging drive-out is power actuated as follows:

A pressure fluid actuated power cylinder 22 is disposed horizontally in longitudinally extending relation above the base 1, beyond the die holder in a direction opposite to the direction of tip-over movement of the latter; said cylinder being supported by rigid end brackets 23. The piston rod 24 of the cylinder 22 projects from said cylinder toward but in normally clearance relation to the die holder, said piston rod forming the forging drive-out rod of this embodiment. The piston rod 24 is disposed to project through the bottom opening of the die when the latter is in tipped over position. The cylinder 22 is double-acting and is energized by conduits 25 fed from a control valve (not shown).

In the operation of this embodiment, the cylinder is suitably actuated to cause the piston rod to engage the bottom end of the forging to drive said forging out of the die.

In the embodiment shown in Fig. 4, the normally upstanding die holder 4b and die 5b are likewise pivoted, as at 26, for movement between a normally upstanding position and a tipped-over laterally opening position. The tip-over mechanism here comprises a double-acting power cylinder 27 disposed longitudinally above the base 1b beyond the die holder in a direction opposite to the direction of tip-over movement thereof.

At its outer end the cylinder 27 is pivotally mounted in connection with a rigid upstanding bracket 28 for limited vertical swinging movement. The piston rod 29 of cylinder 27 is secured centrally to a yoke 30; the legs of the latter straddling the die holder 4b and being pivoted thereto intermediate its top and bottom as at 31. The cylinder 27 is actuated through the medium of conduits 32 fed from a control valve (not shown). As is apparent, actuation of the cylinder 27 to advance the piston rod 29 causes the die holder 4b and die 5b to be tipped from normally upstanding position to a laterally opening position.

In this embodiment no forging drive-out means is employed, due to the fact that the die 5b is of a type employed to form tapered forgings, which can be removed from the die without the necessity of drive-out means. However, if drive-out

means are found desirable, the same may be incorporated in this embodiment of the invention and can be of the manually actuated type shown in Figs. 1 and 2, or the power actuated type, shown in Fig. 3.

From the foregoing description it will be readily seen that we have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described our invention, what we claim as new and useful and desire to secure by Letters Patent is:

1. A forging die and mount assembly comprising a base, a normally upstanding die on the base, means pivotally mounting the die for tip-over movement in one direction, a bellcrank lever pivotally mounted in connection with the base in the other direction from the die and on a parallel axis, and a link pivotally connected in tip-over relation to the die between the latter and one leg of said lever; the other leg of said lever comprising an actuating handle.

2. A device as in claim 1 in which said one leg is relatively short and normally upstanding; the other leg being elongated and normally substantially horizontal.

3. A forging die and mount assembly comprising a base, a normally upstanding, upwardly opening cavity die on the base, means pivoting the die for tip-over movement in one direction to a laterally opening position, said die having a bottom opening, a forging drive out rod, an upstanding guide member slidably mounting said rod above the base in axial alignment with the bottom opening in the die when the latter is in said laterally opening position, said rod being normally clear of the die but axially movable through said opening, an enlarged head on the end of the rod opposite the die, and a compression spring on the rod between the head and guide member.

4. A forging die and mount assembly comprising a base, a normally upstanding die on the base, means pivotally mounting the die for tip-over movement in one direction, a lever pivotally mounted in connection with the base in the other direction from the die and on a parallel axis, and a link pivotally connected in tip-over relation to the die between the latter and said lever; one end portion of said lever comprising an actuating handle.

5. A forging die and mount assembly comprising a base, a normally upstanding, upwardly opening die cavity on the base, means pivoting the die for tip-over movement in one direction to a laterally opening position, said die having a bottom opening, a forging drive out rod, means slidably mounting said rod above the base in axial alignment with the bottom opening in the die when the latter is in said laterally opening position, said rod being normally clear of the die but axially movable through said opening, said mounting means comprising longitudinally spaced brackets upstanding from the base; an enlarged head on the end of the rod opposite the die and a compression spring on the rod between the head and the adjacent bracket.

FLOYD H. WYMAN.
